NUTCRACKER

Alfred L. Kellett, New Hyde Park, N. Y.

Application June 25, 1954, Serial No. 31,176

Term of patent 14 years

(Cl. D44—1)

To all whom it may concern:

Be it known that I, Alfred L. Kellett, a citizen of the United States, residing at New Hyde Park, in the county of Nassau and State of New York, have invented a new, original, and ornamental Design for a Nutcracker, of which the following is a specification, reference being had to the accompanying drawing, forming part thereof.

In the drawing:

Fig. 1 is a side elevational view of a nutcracker, showing my new design;

Fig. 2 is a front elevational view; and

Fig. 3 is a top plan view thereof.

I claim:

The ornamental design for a nutcracker, substantially as shown.
